UNITED STATES PATENT OFFICE.

ROBERT F. SIMMONS, OF ATTLEBOROUGH FALLS, MASSACHUSETTS.

DESIGN FOR A WATCH-CHAIN.

SPECIFICATION forming part of Design No. 15,879, dated February 24, 1885.

Application filed September 2, 1884. Term of patent 7 years.

To all whom it may concern:

Be it known that I, ROBERT F. SIMMONS, of Attleborough Falls, in the county of Bristol and State of Massachusetts, have invented and produced a new and original Design for Watch-Chain Charms, of which the following is a full, clear, and exact description, reference being had to the accompanying drawings, forming a part of this specification.

10 This design relates to charms for watch chains or guards and for the guards for locks, &c.

The leading feature of my design is a miniature horse and sulky, with a driver seated upon the latter, as is shown in the drawings.

15 In the said drawings, Figure 1 is a front view of a watch-chain with my design attached. Fig. 2 is a similar view of a slightly modified form of my design.

20 In the said drawings, A designates one section of the chain or guard, and A' the other section of the same.

B designates my design, which consists of a miniature figure, b, of a horse, a miniature figure, b', of a racing-sulky, and a miniature figure, b'', of a jockey or driver seated upon the sulky.

The above-described design presents a novel, pleasing, and ornamental effect to the eye.

Having thus described my new and original design, I claim as new and desire to secure by Letters Patent—

The design for watch-chains, &c., the same consisting of the sections A A', a miniature figure of a horse, a miniature figure of a sul- 35 ky, and a miniature figure of a driver or jockey, as shown and described.

ROBERT F. SIMMONS.
